UNITED STATES PATENT OFFICE.

HUGO LENTZ, OF HALENSEE, NEAR BERLIN, AND WILHELM VOIT, OF BERLIN, GERMANY.

INERTIA-GOVERNOR.

No. 874,214.

Specification of Letters Patent.

Patented Dec. 17, 1907.

Application filed August 1, 1906. Serial No. 238,721.

To all whom it may concern:

Be it known that we, HUGO LENTZ, a subject of the German Empire, and resident of 123. Kurfürstendamm, Halensee, near Berlin, in the Empire of Germany, engineer, and WILHELM VOIT, a subject of the German Empire, and resident of 10 Grünwaldstrasse, Berlin, (Steglitz,) in the Empire of Germany, engineer, have invented certain new and useful Improvements Relating to Inertia-Governors, of which the following is a specification.

This invention relates to an axial governor for steam engines and the like and the invention has for its object a governor of this kind provided with means for adjusting the same so as to obtain variations in the speed of the engine.

According to the invention the governor is provided with a spring connected at one extremity with the shaft of the engine, and at the other extremity with an inertia ring influenced by centrifugal weights, and the means for adjusting the governor for various speeds of the engine consist in varying the tension of the spring, this being effected by bending the portion thereof connected with the shaft, an adjustable radial pin pressing against said portion.

According to this invention the means for varying the tension of the spring are such as to allow said tension to be varied both when the engine is stopped and when it is running. This object is attained by means of the mechanism represented in the accompanying drawings in which:

Figure 1 illustrates a front elevation of the governor, partly in section, with a mechanism for varying the tension of the spring when the engine is stopped. Figs. 2 and 3 show in front view and longitudinal section respectively, a mechanism for regulating the governor when running. Figs. 4 and 5 illustrate a modified structure for fixing one end of the spring. Fig. 6 shows a modified form of mechanism for regulating when running.

In the drawings: *a* is the shaft, *b* is a double arm keyed upon the shaft, *c c* are the governor pendulums, *d d* are the spindles by means of which the pendulums are connected to the fixed part *b* in such a manner that they are able to rotate around them. The centrifugal pendulums *c c* are connected by means of the pins *e* to the connecting rod *f*.

h is an inertia ring to which the rods *ff* are fitted by means of spindles *g*.

i is a flexion spring, circular or spiral in form, which is fixed to one extremity *i'* by the inertia ring *h* and by the other extremity to the arm *b'*, which is in one piece with the arm *b*. The inertia ring *h* is mounted in such a manner that it is capable of rotating around the shaft *a* to the extent permitted of by its dependence upon the pendulums *c c*. The centrifugal forces developed by the weights of the pendulums *c c* during the rotation of the axial governor cause the inertia ring *h* to rotate relatively to the shaft *a* and extend the spring *i* until the tension of the spring balances these centrifugal forces.

The inertia ring is connected, by means of an appropriate sleeve, to any member to be controlled, such as the eccentric sheaf *s*, shown in Fig. 3, actuating the distributing valve of the machine. The position of this eccentric is thus changed together with that of the inertia ring, and the distributing valve causes the speed of the machine to vary accordingly.

j is a knife edge fitted to the part *b'* fixed on the shaft *a*, *i* is the flexion spring one extremity *i'* of which is formed in the shape of a hook (Figs. 1 and 2) which bears against the knife edge *j*.

k is a screw threaded pin which at a slight distance from the extremity of the spring *i* *i'* presses against the spring and is supported in the tube *b'* fixed on the shaft *a*. This pin may be adjusted by turning the nut *l*. The unscrewing of the pin produces a bending of the spring, that is to say, an increase in the tension of the spring and consequently an increase in the number of the revolutions of the machine. With this construction the variation of the tension of the spring and of the number of revolutions can only be effected while the machine is at rest.

In order to render it possible to vary the number of revolutions even during running, recourse is had to the form of device represented in Figs. 2 and 3. The shaft is bored and the hole drilled in the part *b'* in which the pin *k* is placed is prolonged as far as the said bore in the shaft. The pin *k* is of such a length that it projects into the longitudinal bore of the shaft; *m* is a pin one extremity of which is provided with a groove *n*, the

base of which is cuneiform and constitutes a wedge n' . The pin k^1 enters the groove n and constitutes the rectilinear guidance for the pin m . δ is a rod guided in a straight line in a fixed part of the machine and movable in the direction of its length; this rod is screw threaded and rotatably coupled with the cuneiform pin. p is a nut provided with a hand wheel q (Fig. 3) which by its rotation 10 displaces the rod δ and consequently the cuneiform pin m , n in the direction of its length, in such a manner that the pin k is radially displaced by means of the cuneiform surface n' thereby effecting the variation of 15 the tension of the spring.

A different method of suspending the spring is illustrated in Figs. 4 and 5. v is a bolt supported in the fixed part b' and w is a lever connected with this bolt and capable 20 of rotating with it. This bolt is provided with a slot in which the extremity of the spring i is fixed. The lever w , which is fixed on the bolt, bears against the pin k or k^1 which may be adjusted either as in Fig. 1 by 25 means of a nut (Fig. 4) or as in Figs. 2 and 3 by means of a wedge m (Fig. 5.) In cases in which the shaft of the machine cannot be bored, in order that it may be possible to 30 vary the number of revolutions even during running, the construction shown in Fig. 6 is adopted. In the shaft a there is formed a groove x and in this groove the wedge n' actuating the pin k^1 is movable. To the wedge n' there is fixed a sleeve n^2 provided with 35 two collars r , r' . In order to displace the wedge n' a ring may be arranged between the collars r , r' , said ring engaging by means of trunnions in a regulating lever not shown.

The arrangements described which increase 40 the tension of the spring by bending it, permit of obtaining a greater variation of tension of said spring with a smaller effort.

The inertia governor is applicable to the speed regulation of any engine and permits 45 of varying automatically the position of a distributing member, or the like, connected with said governor, and thereby the number of revolutions of the engine.

Having now particularly described and ascertained the nature of our invention and in what manner the same is to be performed, we declare that what we claim is:—

1. In combination with an engine shaft, a governor comprising a double arm rigidly 55 keyed upon the shaft, two weights pivoted to the extremities of said double arm, an inertia ring surrounding the weights and connected therewith, a flexion spring having one end rigidly fixed to the inertia ring and the other 60 to the double arm, and means for varying the tension of the spring, substantially in the manner and for the purpose specified.

2. In combination with an engine shaft, a governor comprising a double arm rigidly keyed upon the shaft, two pendulums pivoted to the extremities of said double arm, an inertia ring surrounding the weights and connected therewith, a flexion spring having one end rigidly fixed to the inertia ring and the other to the double arm, links connecting 65 the ring with the pendulums and means for varying the tension of the spring. 70

3. In combination with an engine shaft, a governor comprising a double arm rigidly keyed upon the shaft, two weights pivoted to the extremities of said double arm, an inertia ring surrounding the weights and connected therewith, a flexion spring having one end rigidly fixed to the inertia ring and the other to the double arm, links connect- 75 ing the ring with the weights, and means for varying the tension of the spring, consisting of a movable pin radially guided in a tubular portion rigidly fixed to the double arm, one extremity of said pin bearing against the 80 spring.

4. In combination with an engine shaft, a governor comprising a double arm rigidly keyed upon the shaft, two weights pivoted to the extremities of said double arm, an inertia 90 ring surrounding the weights and connected therewith, a flexion spring having one end rigidly fixed to the inertia ring and the other to the double arm, links connecting the ring with the weights, means for varying the tension of the spring, consisting of a movable pin radially guided in a tubular portion rigidly fixed to the double arm, one extremity of said pin bearing against the 95 spring, and means for displacing said pin radially. 100

5. In combination with an engine shaft, a governor comprising two arms rigidly keyed upon the shaft, a knife edge fitted to the extremity of one arm, two pendulums pivoted to the extremities of said arms, an inertia 105 ring, a flexion spring attached at one extremity to the inertia ring, the other extremity being hook-shaped and bearing against the knife edge of one arm, links connecting the ring with the weights, means for varying the tension of the spring consisting of a movable pin radially guided in a tubular portion rigidly fixed to the double arm, one extremity of said pin bearing against the 110 spring, and means for displacing said pin radially. 115

6. In combination with an engine shaft, a governor comprising a double arm rigidly keyed upon the shaft, a bolt supported by one arm, a lever connected with said bolt, 120 two weights pivoted to the extremities of the double arm, an inertia ring surrounding the weights and connected therewith, a flexion spring having one extremity rigidly fixed to

the inertia ring and the other in a slot of the bolt, links connecting the ring with the weights, and means for varying the tension of the spring consisting of a movable pin radially guided in a tubular portion rigidly fixed to the double arm, one extremity of said pin bearing against the spring.

In testimony whereof we have hereunto

placed our hand at Berlin this 28th day of June 1906.

HUGO LENTZ.
WILHELM VOIT.

In the presence of—

WOLDEMAR HAUPT,
HENRY HASPER.
